UNITED STATES PATENT OFFICE

2,656,110

SPLIT CLEARING MECHANISM

Frederick A. Niemann, Chicago, Ill., assignor to
 Felt & Tarrant Manufacturing Company, Chi-
 cago, Ill., a corporation of Illinois

Application April 30, 1947, Serial No. 744,984

8 Claims. (Cl. 235—144)

1

This invention relates in general to calculating machines, and more particularly to the register or accumulator mechanism employed therein.

A principal object of the invention is to render a multidenominational accumulator capable of retaining values entered in some of the denominational orders thereof while permitting others of its denominational orders to be zeroized or cleared of values that have been entered therein.

With this type of calculating machine having only a single accumulator, such as those key-operated machines illustrated in United States Letters Patent No. 762,520, issued June 14, 1904, No. 1,357,748, dated November 2, 1920, or No. 2,346,601, issued April 11, 1944, or the key-responsive machines disclosed in United States Letters Patent No. 2,063,962, and No. 2,402,569, issued December 15, 1936, and June 25, 1946, respectively, inventory computations and many other similar operations are performed as a series of separate steps, in each of which a sub-total is obtained; and in order to get the total of such sub-totals, each of the latter must be written down and the accumulator cleared before the next succeeding one is computed, and these several sub-totals thereafter again must be entered in the machine from such written notations. To facilitate the performance of such calculations, this type of machine has been provided with an auxiliary or secondary accumulator to which sub-totals may be transferred from the primary accumulator, as disclosed in United States Letters Patent No. 2,130,364 issued September 20, 1938, but considerable additional expense is entailed in this solution of the problem presented by such calculations.

The present invention offers a simplified solution of the problem of eliminating the necessity of making written notations of sub-totals in a machine having only one accumulator by enabling the entry of a sub-total, which has been obtained in one portion of the accumulator, into another portion of the same accumulator, and retaining the values in the latter portion during a clearing or zeroizing of the former portion of the accumulator.

Another important object of the invention, therefore, is the provision of inexpensive means which may be incorporated readily in any calculating machine having only a single accumulator

2

so as to convert the latter, in effect, into a primary accumulator and a secondary accumulator.

A further important object of the invention is to provide a calculating machine having an accumulator with a plurality of numeral wheels and means for clearing or zeroizing the same, with normally ineffective means selectively operable to prevent clearing of some of the numeral wheels during zeroizing of the accumulator.

10 Another object of the invention is the provision of novel indicating means, associated with the keyboard of a calculating machine incorporating such selectively operable means, for indicating which of the numeral wheels of the several denominational orders of the accumulator will not be cleared in a zeroizing operation when the selectively operable means have been rendered effective.

15 Another object of the invention is to so construct such normally ineffective, selectively settable means as automatically to effect zeroizing of those numeral wheels prevented from being cleared during a normal zeroizing operation, upon subsequent selective setting of said means back to normal ineffective position.

20 Another object of the invention is the provision of two selectively operable control members which, by virtue of their sequence or manner of operation, effect zeroizing of all the numeral wheels, only a first group of such numeral wheels, or such first group and then the remaining ones of the numeral wheels of an accumulator.

25 Numerous other objects and advantages of the invention will be apparent as it is better understood from the following description, which, when taken in connection with the accompanying drawings, discloses a preferred embodiment thereof.

In the drawings,

30 Fig. 1 is a top plan view of a calculating machine embodying the features of the present invention;

35 Fig. 2 is an enlarged plan view of the accumulator dividing indicating member which is adapted to be mounted on the keyboard in the manner illustrated in Fig. 1;

40 Fig. 3 is an enlarged front elevation of the machine of Fig. 1 with the casing removed;

45 Fig. 4 is a top plan view of the accumulator zeroizing preventing control shaft shown in Fig. 3;

Fig. 5 is a side elevational view of the machine, as seen from the right side of Fig. 1, with parts of the casing broken away;

Fig. 6 is a detail side elevation of the accumulator swinging frame as seen from the left side of Fig. 1;

Fig. 7 is an enlarged vertical section through the forward part of the machine, as viewed from the left side of Fig. 1, showing the accumulator and part of the zeroizing mechanism in normal position;

Fig. 8 is a detail vertical section looking forwardly of the machine and taken substantially on the line 8—8 of Fig. 7;

Fig. 9 is a side elevation of the forward part of the machine, with the casing in section, similar to Fig. 5 and showing the accumulator zeroizing control key in effective position;

Fig. 10 is a view similar to Fig. 7 showing the swinging frame of the accumulator moved forwardly in zeroizing;

Fig. 11 is a detail side elevation, as seen from the left side of Fig. 1 and with parts in section, showing the mechanism for returning the swinging frame of the accumulator rearwardly to normal position in response to digit key actuation; and

Fig. 12 is a view similar to Fig. 11 showing the position of the parts assumed after zeroizing of the accumulator when the latter is in its de-trained position of Fig. 10.

Referring more particularly to the drawings, the instant embodiment of the invention is shown for purposes of illustration as being incorporated in a calculating machine of the multiple order key-driven type disclosed more specifically in my prior Patent No. 2,346,601 and in Patent No. 1,357,748 hereinbefore referred to. As the details of construction of this type of machine readily may be understood from these patents, a brief description of the general features thereof, and more specific explanation of such parts as are directly concerned with the operation of the present improvements, are thought to be sufficient for a complete understanding of this invention.

As disclosed in the last mentioned patents, the various instrumentalities of the calculating machine are supported by a frame mounted on a base 21 of a suitable casing and consisting essentially of side skeleton plates 22 and intermediate skeleton plates 23 disposed between the various mechanisms of the several denominational orders of the machine and tied together at suitable points by transverse tie-rods 24. For convenience, the same reference characters will be employed hereinafter as are used in the last two patents above referred to for designating similar parts of the machine.

A number of columns of nine keys each are provided, herein illustrated as twelve, each digit key of which is indicated by reference numeral 25, and an accumulator mechanism is mounted at the forward end of the casing which includes numeral wheels operable directly in response to actuation of the keys in each of the several columns. The keys 25 are adapted to actuate the numeral wheel in the associated denominational order through the agency of their stems 27 cooperating with a column actuator 26 (Fig. 5) in the form of a segment lever pivoted at the rear of the machine. It will be understood that there is a column actuator 26 provided in each denominational order for operation by the nine digit keys of that order. At the forward oscillatable end, each column actuator 26 is provided with a rack 28 which

meshes at all times with an accumulator pinion 29 mounted for rotation on a transverse shaft 30 extending across the machine and suitably journaled in the skeleton frame plates. The pinion 29 of each denominational order forms a part of an internal ratchet mechanism (not shown) for drivingly connecting the rack 28 with a transmitting or actuating gear 31 during an up-stroke of the column actuator 26, the down-stroke of the column actuator being idle so far as the accumulator mechanism is concerned. Such rotation of the transmitting pinion 31, resulting from upward movement of the associated column actuator 26, is transmitted, through a numeral wheel driving gear train including a carrying gear 32 (Fig. 7) rotatable on a transverse shaft 33 and adapted to mesh with the transmitting gear 31, an intermediate gear 34 rotatable on a transverse shaft 35 and in mesh with the carrying gear 32, and a numeral wheel gear 36 rotatable on a transverse shaft 37 and in mesh with the intermediate gear 34, to a numeral wheel 38 fixed to the gear 36 for rotation therewith on the shaft 37. The shafts 30, 35 and 37 are suitably supported by the skeleton frame plates in fixed relationship with one another, and the shaft 33 is carried in a swinging frame comprising transversely spaced partition plates 64 (Fig. 6) connected together by suitable tie-rods 65. The swinging frame carrying the shaft 33 is mounted for limited pivotal movement on the shaft 35 to permit movement of the carrying gears 32 from their normal meshing relationship with the respective transmitting or actuating gears 31, as shown in Fig. 7, to the de-trained position illustrated in Figs. 6 and 10, in zeroizing or clearing the numeral wheels of the accumulator.

As noted hereinbefore, downward movement of any column actuator, through the agency of the ratchet between the accumulator gear 29 and the transmitting gear 31, results in no motion being transmitted through the associated gear train to the numeral wheel 38. The extent of such downward movement will be determined by the particular digit key 25 depressed, the "1" key being spaced a sufficiently greater distance from the pivot of the column actuator 26 than the "9" key so that actuator of the "1" key will depress the column actuator only one-ninth as far as will depression of the "9" key. The remaining digit keys 25 therebetween in each column will similarly proportionately effect depression of the associated column actuator in amounts corresponding to their digital values. Upon release of any digit key 25 following complete depression thereof, the column actuator 26 moved downwardly thereby will be returned upwardly to its normal position by springs 39 associated therewith (Fig. 5) to effect rotation of the numeral wheel 38 in that denominational order an amount corresponding to the digital value of the key 25 employed to depress the column actuator.

As illustrated in detail in Patent No. 1,357,748 previously cited, zeroizing of the numeral wheels 38 of this accumulator is accomplished in the present machine by forward swinging of the accumulator frame comprising the partition plates 64 and tie-rods 65 to detrain the carrying gears 32 from the transmitting gears 31. In other words, the swinging frame of the accumulator is moved from its position of Fig. 7 to that shown in Fig. 10. This is accomplished through the agency of a zeroizing lever 71, shown in Fig. 5 is pivoted at its lower end on a transverse shaft 70 journaled in the right hand side plate 22 of

the machine frame. A segment 72 is fixed upon the inner end of the shaft 70 and a link 73 is pivotally connected at its rear end to the segment 72 and at its forward end to a depending lever 74 that is pivoted at 75 on the fixed frame. The lower end of the lever 74 is pivotally connected by means of a short link 76 with an arm 77 rotatably mounted upon a transverse shaft 78 that is journaled in the skeleton frame members. The arm 77 is provided with a transversely extending engaging face 79 adapted to contact a second arm 80 secured to the shaft 78. When these parts are in their normal positions of Fig. 5, a short swinging movement of the zeroizing lever 71 forwardly (to the left therein) through the segment 72, link 73, lever arm 74, short link 76, arm 77 and rocker arm 80 will impart a rocking movement to the shaft 78 forwardly, or in a counterclockwise direction as viewed in this figure.

Additional rocker arms 81 (Figs. 7 and 10) are fixed in space relationship to each other on the transverse shaft 78 for rotation therewith. These rocker arms 81 are pivotally connected with curved links 82 having slotted shifting pivots upon a transverse shaft 83. The forward end of each of the curved links 82 is provided with a pin 84 positioned between the spaced jaws 85 of an inner member 86 of a toggle. Each toggle member 86 is pivoted on a transverse shaft 87 carried by the swinging frame plates 64 of the accumulator, and the outer end of each toggle member 86 is pivotally connected with the other or outer member 88 of the toggle. The several toggle members 88 are pivoted on studs 89 mounted on the fixed skeleton frame members, and are provided with depending arms having stop projections 91 adapted to engage the toggle members 86 to limit their movement upon forward rocking of the shaft 78 from its position of Fig. 7 to that of Fig. 10 (clockwise in these figures).

When the swinging frame of the accumulator is in such position that the gears 32 are in mesh with the gears 31, i. e., the normal position of the parts during operation of the machine, the links 82 and toggles 86-88 occupy the position illustrated in Figs. 7 and 11. Upon operation of the zeroizing lever 71 to effect cancelling, i. e., toward the left as view in Fig. 5, the link and lever connection previously described imparts rotation to the shaft 78 to move the curved links 82 from their position of Fig. 7 to that of Fig. 10. In so moving, the pins 84 push down on the lower jaws of the toggle members 86, thereby throwing the toggles 86-88 past their dead centers to the position illustrated in Figs. 10 and 12. As the toggle members 86 are pivoted at 87 to the respective plates 64 of the swinging frame, such movement of the toggles past their dead centers is accompanied by a forward or outward swinging of the accumulator frame with a resultant detraining of the winding gears 32 from the gears 31.

Detraining the carrying gears 32 from the gears 31 leaves the carrying springs (not shown) free to unwind, those associated with any of the numeral wheels which have been actuated having been wound up in the manner described in said Patent No. 1,357,748, and such unwinding occurs until the numeral wheels arrive at zero position. This unwinding action of the respective carrying springs is terminated by suitable stops (not shown) which are projected into operative position by the toggles 86-88. These stops are normally in inoperative position, and upon being moved to operative position by the toggles, lie in

the path of either one or the other of two fixed stops 97 (Fig. 10) appropriately located on the face of each winding gear 32. As soon as one of the stops 97 comes into contact with such stop members, the unwinding action of the carrying springs is terminated and the numeral wheels are held in zero position.

The swinging frame of the accumulator is retained in its outward and forward position, after 10 a zeroizing operation thus has been effected, and the gears 32 are maintained in disengagement with respect to the gears 31, until the subsequent operation of any one of the digit keys 25. The swinging frame is restored to position for entraining the winding gears 32 with the gears 31 upon the next actuation of a key 25 after a zeroizing operation has been affected by means of the mechanism best shown in Figs. 5, 11 and 12. Fixed on the shaft 78 is an upstanding arm 105, 20 and pivoted on the upper end of this arm is a link 106 to which is attached a spring 107 that extends to, and is connected with, the fixed frame of the machine. A toggle member 109 has a slotted pivot at one end on the arm 105, and the other 25 end thereof is pivotally connected with a second toggle member 110. The toggle member 110 in turn is pivoted on a transverse shaft 111 supported by the fixed frame of the machine. A spring 114 connects the toggle member 110 with the fixed frame, the spring 114 normally being under tension and the spring 107 relaxed. The parts occupy the position illustrated in Fig. 11 when the swinging frame of the accumulator is in its normal position, with the gears 31 and 32 in 30 mesh. On movement of the shaft 78 by the zeroizing lever 71, the arm 105 draws the opposite members 109 and 110 of this detraining toggle into the position shown in Fig. 12, the intermediate pivot point of the toggle being shifted past its dead center. This movement of the toggle is assisted by the power stored up in the spring 114.

Concurrently with such movement, however, the spring 107 is placed under tension, and is so held by the movement of the intermediate pivot of the toggle past dead center.

Formed on the toggle member 110 is an upstanding arm 115 adapted to be projected, on movement of the toggle into the gear-detained position shown in Fig. 12, into the path of a pin 116 carried by the upper end of an arm 117 that is fast on the transverse shaft 111. Pivoted to the upper end of arm 117 is a link 118 which extends rearwardly of the machine (to the left in Figs. 11 and 12) and has its rear end pivoted on a transverse shifting bar 119 that is supported by vertical arms 120 upstanding from, and connected to, a transverse rock bar 121 journaled in suitable bearings on the opposite sides of the fixed skeleton frame members.

Pivoted on a transverse shaft 122 (Fig. 5) supported by the fixed frame of the machine, are resistance levers 123 respectively corresponding with the several columns or orders of the machine and having their lower ends extended into the path of movement of the shifting bar 119. The upper ends of these levers 123 are attached to springs 124 extending to a fixed part of the frame and adapted normally to draw the upper ends of 60 said levers 123 rearwardly (to the right in Fig. 5 and to the left in Fig. 11) and thus to maintain their lower ends out of engagement with the shifting bar 119. Each resistance lever 123 is provided adjacent its lower end with a forwardly and downwardly inclined cam edge 125 adapted to be

engaged by a dolly roll 126 supported by the corresponding column actuator 26.

On movement of the toggle 109-110 to the position illustrated in Fig. 12, by the operation of the zeroizing lever hereinbefore described, the engagement of arm 115 with pin 116 of arm 117 imparts a slight forward movement to the arm 117 (to the right in Fig. 12), and in so doing shifts the link 118 forwardly. Such forward movement of link 118 draws the shifting bar 119 forwardly into a position that is just to the rear of the depending portions of the several resistance levers 123. Such are the positions of the several parts upon the completion of a zeroizing movement of the cancelling lever 71, and all of the 15 parts remain in these positions until the subsequent actuation of any digit key 25 and the consequent depression of its companion column actuator 26.

The depression of a column actuator 26 causes its dolly roll 126 to ride down the inclined cam edge of the cooperating lever 123, and in so doing effects a rearward movement of the roll and of said lever 123 (to the left in Fig. 12). This rearward movement of the lever 123 engages the lever with the shifting bar 119 and, in so doing, shifts the bar 119 rearwardly to impart a slight rearward movement to the link 118. Rearward shifting of link 118 causes arm 117 to move rearwardly, and the consequent rearward movement of pin 116 imparts a rearward movement to the upstanding arm 115 of the toggle member 110, and in so doing, the intermediate pivot of the toggle 109-110 is shifted rearwardly past dead center. As soon as the intermediate pivot of the toggle 109-110 thus moves past dead center, the spring 107 is released and the power stored therein completes the movement of the toggle back into the normal position illustrated in Fig. 11. Through the consequent rearward rocking movement imparted to the shaft 78 by the arm 105, the toggle 36-38 is restored to its normal position of Fig. 7, swinging the accumulator frame inwardly to again entrain the gears 31 and 32. The above described movement of the 45 toggle 36-38 and shaft 78 restores the arm 80 into position for being engaged by the arm 77, upon the next cancelling movement of the zeroizing lever 71.

Means are provided for preventing misoperation of the machine by partial depression of a digit key 25 (which locks the associated column actuator 26 in partially depressed position, such as shown in Fig. 5, in well-known manner in this type of machine) and subsequent operation of the zeroizing lever 71. This means, which is described in detail in U. S. Letters Patent No. 1,902,597, issued March 21, 1933, is illustrated in Fig. 5, and includes a link 151 pivoted at its rear end on the shifting bar 119 and having at its forward end a slot 152 which is arranged to slide back and forth as rock bar 121 is rocked back and forth, when a column actuator 26 is depressed and then rises to normal position, on a stud 153 fixed in a latch 154 pivoted on a tie-rod 155. A spring 156 is arranged to connect the link 151 and the perpendicular arm of the latch 154 together to normally keep the stud 153 at the rear end of the slot 152. Whenever the rock bar 121 is rocked rearwardly by a depressed segment lever 26 and its associated resistance lever 123, the latch 154 will be raised to its position of Fig. 5. The latch 154 constitutes a zeroizing mechanism lock and is provided with a bent lip 157 above which is arranged a latch arm 158

depending from, and forming a part of, the zeroizing segment 72. The result of such arrangement is that in the event an operator makes a partial key stroke and leaves the segment lever 26 depressed, the resistance lever 123, through its contact with the rod 119 of the rock bar 121, will cause the latter to rock rearwardly and hold it in the position of Fig. 5, until the segment lever 26 rises to its normal upper position following a corrective actuation of the partially depressed digit key. This rearward rocking of bar 121 will cause the raising of the latch 154 to bring the lip 157 into contact with the latch arm 158. Thus, if the operator should zeroize the machine while a segment lever lock is so set with the segment lever 26 depressed, the latch arm 158, in swinging rearwardly, will depress the lip 157 causing the stud to move in the slot 152, and the spring 156 to give way, until the latch arm 158 has passed the lip 157, when the spring 156 will cause the latch 157 to engage the arm 158 to prevent the return of the zeroizing lever and the return of the shaft 78 by spring 107. The toggle 109-110 thus is held, through action of 121, 119, 151, 154, 158, 25 73, 74, 76, 77, 79, 80, 78, 105, and 110, against spring 107 in toggle forming position for spring 114 to throw it past dead center. The toggle 109-110 is maintained in this position and the accumulator swinging frame is held detained until the segment lever or actuator 26 has returned to its normal position, at which time the roll 126 will allow the lever 123 to return to normal position and the rock bar 121 to swing forward and thus allow links 151 and 118, which are operated simultaneously by 121, to move forward. When link 118 thus moves forward, it releases the detaining toggle 109-110 and, since this toggle is being held in toggle forming position by means of the above-described mechanism including 121, 40 151, 154, 153, 78, and 105, the spring 114 throws the toggle past its dead center into the position shown in Fig. 12 to lock the swinging accumulator frame and the shaft 78 against the normal return gear-entraining movement under spring 107 before the latch 154 can restore to normal upon the disengagement of lip 157 from the arm 158 by the same movement of 121 that releases toggle 109-110 from arm 118. The detaining toggle 109-110 continues in its made-up position of Fig. 12 and holds gears 31 and 32 out of registering engagement with each other as shown in Fig. 10 until another calculating operation is begun, at which time, as soon as any digit key 25 is depressed, its column actuator causes roll 126 to move the lever 123 rearwardly which engages and moves rod 119 rearwardly to rock bar 121. The rocking of bar 121 pulls the arm 118 rearwardly which breaks the detaining toggle 109-110 from its position of Fig. 12 to its position of Fig. 11, which permits the swinging accumulator frame to return to the position shown in Fig. 7, and thereby effects entrainment of the gears 31 and 32 of the accumulator before the depressed column actuator starts rising to 55 60 65 70 75 actuate the accumulator mechanism.

The instant invention comprises the addition to a calculating machine, such as that above-described, of means selectively operable to effect clearing of only some of the numeral wheels 38 upon operation of the zeroizing lever 71, so that any values contained in the remainder of the accumulator will be retained therein. This means includes a zeroizing control key 201 (Figs. 1, 3, 5 and 9) located in the lower right-hand portion 75 of the machine, extending downwardly through a

suitable slot in the casing, and pivotally connected at its lower end to the rear end of a walking beam or lever 202. The lever 202 is pivotally mounted intermediate its ends on the transverse shaft 83. The lower end of the control key 201, forwardly of its pivotal connection with the lever 202, is connected to the lower end of a spring 203, the upper end of which is connected to a stud or pin 204 mounted on and extending outwardly from the right-hand side skeleton plate 22, as best seen in Fig. 3. The outer end of the stud 204 normally engages a lip or shelf 205 provided on the rear edge of the stem of the control key 201, as shown in Fig. 5, to limit upward movement of the control key in response to the action of the spring 203. The slot in the upper surface of the machine casing through which the control key 201 extends insures engagement of the shelf 205 with the stud 204 by limiting forward movement of the upper portion of the control key. Above the shelf 205, the control key 201 is also provided on its rear edge with an opposed lip or shelf 206 and an undercut recess 207. When moved downwardly from its position of Fig. 5, the control key 201 is limited in such downward movement by engagement of the shelf 206 with the stud 204, and the control key may be latched in such lower or operative position by rearward movement to cause engagement of the stud 204 in the recess 207, as shown in Fig. 9. Release of the control key 201 after movement to this operative position will result in the key being retained therein by the spring 203 maintaining the undercut portion of the recess 207 in engagement with the stud 204. To release the control key 201 from such lower or operative position, it is necessary only for an operator to depress the key slightly and move the upper end thereof forwardly to permit the spring 203 to return it to the upper or inoperative position of Fig. 5.

The forward end of the lever 202 is slotted for pivotal engagement with the reduced portion of a pin 208 mounted in any suitable manner in the rear end of a crank arm 209. The crank arm 209 is provided with a rectangular recess at its forward end through which a milled or flattened end portion of a transverse control shaft 211 extends. The crank arm 209 is thus secured to the shaft 211, as best shown in Fig. 4. The shaft 211 extends across the front of the machine, as illustrated in Fig. 3, and is journaled in suitable apertures in the upper ends of the vertical arms of spaced levers or brackets 212. Three of these brackets 212 preferably are provided, each being in the form of an angle lever mounted at its central portion on the tie-rod 24 disposed at the lower front end of the machine, and held against rotation thereon by engagement of the rearwardly extending arm thereof with the transverse shaft 83. The brackets 212 are held against adjacently disposed skeleton frame plates of the machine by suitable spacers mounted on the tie-rod 24 to prevent displacement thereof longitudinally of the shaft 211. At each side of the rightmost supporting bracket 212, the control shaft 211 is provided with annular grooves 213 (Fig. 4) within which suitable spring washers or clips 214 (Fig. 3) may be mounted, after the shaft 211 has been assembled in the machine, to prevent longitudinal movement of the shaft.

A plurality of detent levers, indicated generally by reference numeral 215, are mounted at the forward end of the machine in those denominational orders in which it is desired to prevent

zeroizing of the numeral wheels of the accumulator in response to operation of the zeroizing lever 71. In the present embodiment of the invention, which is incorporated in a twelve column machine, these detent levers 215 are illustrated (Fig. 3) as being associated with each of the six highest denominational orders. Each of the levers 215 is provided at its lower end with a pair of rearwardly extending slotted arms 216 (Fig. 8) bent from and formed integrally with the main body portion thereof. As shown in Fig. 8, each of these arms 216 engages and embraces a reduced end portion 217 of a spacer collar 218 mounted on the forward lowermost tie-rod 24. Each detent lever 215 is thus mounted for rotation on the tie-rod 24 and retained in proper lateral position thereon by the enlarged central portion of the associated collar 218. The main body portion of each of the detent levers 215 is provided with a loop portion 219 stuck rearwardly therefrom for anchoring engagement with the forward end of a spring 221, the rear end of which engages the transverse shaft 83 (Fig. 7). The springs 221 thus hold the detent levers 215 on the spacer collars 218 and against the forward portion of the control shaft 211. At its upper end, each of the detent levers 215 is provided with a rearwardly extending finger 222 adapted to cooperate with the associated carry winding gear 32 of the accumulator. The control shaft 211 is provided with a flat surface 223 (Figs. 3, 4, and 7) extending across those denominational orders in which detent levers 215 are mounted. When the control shaft 211 has been rotated to its operative position of Fig. 9 by depression of control key 201 from its inoperative position of Fig. 5, this flat portion 223 of the shaft is in the plane of the main body portions of the detent levers 215, so that the springs 221 hold the detent levers in their rearmost operative positions of Figs. 7, 9, and 10. When so disposed, the rear ends of the finger 222 of the detent levers will engage between the teeth of the associated carry winding gears 32 when the latter are moved forwardly in a zeroizing operation by the forward swinging of the accumulator frame plates 64 in response to operation of the zeroizing lever 71. As seen in Figs. 7 and 9, however, the fingers 222 clear the gears 32 when the accumulator is in its normal position wherein the gears 32 are in mesh with the gears 31. Rotation of the control shaft 211 to its operative position of Fig. 5 by the spring 203, upon release of the control key 201 from its operative position of Fig. 9 as hereinbefore described, results in all of the detent levers 215 being cammed forwardly against the action of the springs 221, the flat portion 223 of the shaft 211 being removed from alignment with the main body portions of the detent levers 215 and the latter being swung about the tie-rod 24 by that portion of the shaft 211 directly below the flat 223.

Means are provided for indicating to the machine operator which denominational orders of the accumulator will not be cleared by operation of the zeroizing lever 71 when the control key 201 is in its operative position. This means is necessary because only the control key 201 of the above-described mechanism is visible to the operator when the machine casing is in place. The means herein illustrated for accomplishing this indicating function comprises a bar indicated generally by reference numeral 224 and shown in Figs. 1, 2, and 3. This indicating bar 224 is adapted to be mounted on the keyboard of the machine between any two adjacent col-

ums of digit keys 25, and for this purpose is provided adjacent each end with laterally extending, notched shoulders 225 slidably engageable with the stems 27 of the end keys of each adjacent column. The forward shoulders 225 thus prevent forward movement of the indicating bar 224, and the rear shoulders similarly prevent rearward shifting of the bar on the keyboard. In order to prevent unauthorized removal and change of location of the indicating bar 224 from its proper position, the rear end thereof is bent downwardly to be disposed beneath the central portion of the machine casting, as shown in broken lines in Fig. 1. The bar 224 thus indicates the line of division within the accumulator occasioned by the provision of detent levers 215 in some of the denominational orders thereof.

From the above description, it will be seen that means are provided whereby the single accumulator of the machine, in effect, selectively may be converted into two accumulators. By depressing the zeroizing control key 201 and latching the same in its operative position of Fig. 9, the machine may be employed to obtain the total of a number of items in the lower or right-hand half thereof. The operator may then transfer such total appearing in the numeral wheels 38 of the lower half of the accumulator to the upper or leftmost portion of the accumulator by depression of appropriate digit keys 25 to the left of the indicator bar 224. Operation of the zeroizing lever 71 will then effect clearing of the numeral wheels 38 of the lower portion of the accumulator in the manner previously described. However, such zeroizing operation will not affect those numeral wheels 38 with which detent levers 215 are associated, since the forward movement of the winding gears 32 in those orders by the swinging frame of the accumulator will result in such gears 32 being restrained against return to zero position by the fingers 222 of the detent levers. Subsequent operation of any digit key 25 will return the swinging frame of the accumulator to its normal rearward position to re-engage the gears 32 with the numeral wheels 38, and in those denominational orders containing the detent levers 215 the numeral wheels will retain the same positions had prior to the operation of the zeroizing lever 71. This sequence of operations may be repeated as often as desired, the total entered in the leftmost portion of the accumulator being retained therein during zeroizing of the remaining numeral wheels of the accumulator.

After a clearing operation of the lever 71, the numeral wheels of the accumulator in those orders containing the detent levers 215 may be zeroized merely by release of the zeroizing control key 201, since return of the control key 201 to its inoperative position of Fig. 5 will result in disengagement of the fingers 222 from the gears 32 in the manner previously described to permit return of the numeral wheels in these orders to zero by their carry winding springs. Whenever the zeroizing control key 201 is in its inoperative position of Fig. 5, actuation of the zeroizing lever 71 will result in clearing of all the numeral wheels of the accumulator.

It will be understood that the instant mechanism lends itself for use with any desired number or particular ones of the individual numeral wheels of an accumulator, and that the present illustrations thereof are not intended to limit its use to any particular denominational orders.

For example, the flattened portion 223 of the control shaft 211 may be extended completely across the accumulator. Then, in any denominational orders in which it is desired to prevent zeroizing of the numeral wheels, it is necessary only to mount a detent lever 215 and its retaining spring 221. Thus the accumulator may be divided into more than two separate sections, each comprising some of the numeral wheels thereof, and one or more of such sections being provided with the detent levers 215, while one or more of such sections do not have the detent levers 215 mounted therein. With such an arrangement, a plurality of indicator bars 224 are used to separate the keyboard into the corresponding number of sections. In all modifications of the present invention, the indicator bar or bars 224 visually apprise the machine operator as to which denominational orders will not be zeroized, when the zeroizing control key 201 is in its effective position, upon actuation of the zeroizing lever 71.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the forms hereinbefore described being merely preferred embodiments thereof.

I claim:

1. In a calculating machine having a multi-denominational order accumulator with a numeral wheel, a carrying gear and a carry winding spring in each order, an actuator for said accumulator including an actuating gear normally engaged with each said carrying gear, and zeroizing means selectively operable to detrain said carrying and actuating gears to permit said carrying winding springs to return all of said numeral wheels to zero position to clear said accumulator; a selectively operable control member, and normally inoperative detent mechanism mounted in certain of the orders of said accumulator and movable into operative position in response to operation of said control member to cooperate with said carrying gears in said certain orders to prevent return of their associated numeral wheels to zero position by their associated carry winding springs upon operation of said zeroizing means.

2. In a calculating machine having a multi-denominational order accumulator with a numeral wheel, a carrying gear and a carry winding spring in each order, an actuator for said accumulator including an actuating gear normally engaged with each said carrying gear, and zeroizing means selectively operable to detrain said carrying and actuating gears to permit said carry winding springs to return all of said numeral wheels to zero position to clear said accumulator; a selectively operable control member, and normally inoperative detent members mounted in certain of the orders of said accumulator and movable into operative position in response to operation of said control member for engagement by said carrying gears in said certain orders, upon detraining of said carrying and actuating gears in response to operation of said zeroizing means, to prevent clearing of the numeral wheels in said certain denominational orders of the accumulator.

3. In a calculating machine having a multi-denominational order accumulator with a nu-

meral wheel, a carrying gear and a carry winding spring in each order, an actuator for said accumulator including an actuating gear normally engaged with each said carrying gear, a plurality of ordinal columns of depressible digit keys for controlling operation of said actuator, zeroizing means selectively operable to detrain said carrying and actuating gears to permit said carry winding springs to return all of said numeral wheels to zero position to clear said accumulator, and means for maintaining said carrying and actuating gears detrained following operation of said zeroizing means and operable, in response to subsequent depression of any of said digit keys, to re-engage said carrying and actuating gears; a selectively operable control member, and normally ineffective means mounted in a plurality of denominational orders of said accumulator and rendered effective by said control member to cooperate with the associate said carrying gears to prevent clearing of the numeral wheels in said plurality of orders, upon operation of said zeroizing means, and to retain the numeral wheels in said plurality of orders in the same positions occupied at the time of operation of said zeroizing means and until subsequent re-engagement of said carrying and actuating gears in response to depression of a said digit key.

4. In a calculating machine having a multi-denominational order accumulator with a numeral wheel, a carrying gear and a carry winding spring in each order, an actuator for said accumulator including an actuating gear normally engaged with each said carrying gear, a plurality of ordinal columns of depressible digit keys for controlling operation of said actuator, zeroizing means selectively operable to detrain said carrying and actuating gears to permit said carry winding springs to return all of said numeral wheels to zero position to clear said accumulator, and means for maintaining said carrying and actuating gears detrained following operation of said zeroizing means and operable, in response to subsequent depression of any of said digit keys, to re-engage said carrying and actuating gears; normally inoperative detents mounted in a plurality of orders of said accumulator and movable into operative position to cooperate with the associated said carrying gears to prevent clearing of the numeral wheels in said plurality of orders, upon operation of said zeroizing means, and control means selectively movable to one position to cause movement of said detents into operative position, and movable to another position, after operation of said zeroizing means and before subsequent depression of any of said digit keys, to cause movement of said detents into inoperative position to cause automatic clearing of the numeral wheels of said plurality of orders by their associated carry winding springs.

5. In a calculating machine having a multi-denominational order accumulator with a numeral wheel, a carrying gear and a carry winding spring in each order, an actuator for said accumulator including an actuating gear normally engaged with each said carrying gear, and zeroizing means selectively operable to detrain said carrying and actuating gears to permit said carry winding springs to return all of said numeral wheels to zero position to clear said accumulator; means for dividing said accumulator into a plurality of accumulators by preventing clearing of the numeral wheels of selected denominational orders thereof, upon operation of said zeroizing means, comprising a trans-ordinal shaft rotat-

ably mounted adjacent said accumulator and having a flat portion thereon, a detent lever pivotally mounted for engagement with said shaft in each of said selected orders of said accumulator and having a finger which, when in operative position, is engageable with a said carrying gear during detraining thereof by said zeroizing means, spring means for maintaining said detent levers in engagement with said shaft, and control means selectively operable to rotate said shaft to a first position for moving said detent levers to inoperative position to maintain said fingers out of engagement with said carrying gears, and to a second position to align said flat portion thereon with said detent levers to enable said spring means to move said fingers into operative position.

6. In a calculating machine having a multi-denominational order accumulator with a numeral wheel, a numeral wheel driving gear train including a carrying gear, and a carry winding spring in each order; an actuator for said accumulator including an actuating gear normally engaged with said carrying gear to drive said gear train; and zeroizing means selectively operable to detrain said carrying and actuating gears to permit said carry winding springs to return all of said numeral wheels to zero position to clear said accumulator; a selectively operable control member, and normally inoperative detent mechanism mounted in certain of the orders of said accumulator and movable into operative position in response to operation of said control member to cooperate with said gear trains in said certain orders to prevent return of their associated numeral wheels to zero position by their associated carry winding springs upon operation of said zeroizing means.

7. In a calculating machine having a multi-denominational order accumulator with a numeral wheel, a numeral wheel driving gear train including a carrying gear, and a carry winding spring in each order; an actuator for said accumulator including an actuating gear normally engaged with each said carrying gear to drive said gear train; a plurality of ordinal columns of depressible digit keys for controlling operation of said actuator; zeroizing means selectively operable to detrain said carrying and actuating gears to permit said carry winding springs to return all of said numeral wheels to zero position to clear said accumulator; and means for maintaining said carrying and actuating gears detrained following operation of said zeroizing means and operable, in response to subsequent depression of any of said digit keys, to re-engage said carrying and actuating gears; a selectively operable control member, and normally inoperative detent members mounted in certain of the orders of said accumulator and movable into operative position in response to operation of said control member and subsequent operation of said zeroizing means for engagement with said gear trains in said certain orders to retain the numeral wheels in said certain orders in the same relative positions occupied at the time of operation of said zeroizing means and until subsequent re-engagement of said carrying and actuating gears in response to depression of a said digit key.

8. In a calculating machine having a multi-denominational order accumulator with a numeral wheel, a numeral wheel driving gear train including a carrying gear, and a carry winding spring in each order; an actuator for said accumulator including an actuating member for driv-

ing each said gear train to cause the carrying gear therein to wind up its associated carry winding spring; and zeroizing means selectively operable to permit said carry winding springs to unwind to return all of said numeral wheels to zero position to clear said accumulator; a selectively operable control member, and normally inoperative detent mechanism mounted in certain of the orders of said accumulator and movable into operative position in response to operation of said control member to cooperate with said gear trains in said certain orders to prevent return of their associated numeral wheels to zero position by their associated carry winding springs upon operation of said zeroizing means.

FREDERICK A. NIEMANN.
